METAL PICK-UP DEVICE

Lillian D. Westermann, 255 E. 2nd St.,
Redwood Falls, Minn. 56283

Filed June 25, 1970, Ser. No. 23,669

Term of patent 14 years

Int. Cl. D8—05

U.S. Cl. D8—14

FIG. 2

FIG. 1

FIG. 3

FIG. 5

FIG. 4

FIG. 1 is a front elevational view of the metal pick-up device showing my new design;

FIG. 2 is a top plan view of FIG. 1;

FIG. 3 is a side elevational view of FIG. 1;

FIG. 4 is an enlarged bottom plan view of FIG. 1 showing the metal pick-up head of the device; and

FIG. 5 is an enlarged cross sectional view taken along the line 5—5 of FIG. 1.

I claim:

The ornamental design for a metal pick-up device, substantially as shown and described.
